UNITED STATES PATENT OFFICE

157,825

TELEPHONE SHELF

Robert K. Abbott, Columbus, Ohio

Application April 22, 1949, Serial No. 2,195

Term of patent 7 years

(Cl. D33—3)

To all whom it may concern:

Be it known that I, Robert K. Abbott, a citizen of the United States, residing at Columbus, in the county of Franklin and State of Ohio, have invented a new, original, and ornamental Design for a Telephone Shelf, of which the following is a specification, reference being had to the accompanying drawings, forming a part thereof.

I claim:

The ornamental design for a telephone shelf, as shown.

ROBERT K. ABBOTT.
